UNITED STATES PATENT OFFICE.

RICHARD G. RAND, OF KERNERSVILLE, NORTH CAROLINA.

BRICK-MACHINE.

1,095,596.

Specification of Letters Patent. Patented May 5, 1914.

Application filed September 11, 1911. Serial No. 648,692.

To all whom it may concern:

Be it known that I, RICHARD G. RAND, a citizen of the United States, residing at Kernersville, in the county of Forsyth and State of North Carolina, have invented a new and useful Brick-Machine; and I do hereby declare the following to be a full, clear, and exact description of the invention, such as will enable others skilled in the art 10 to which it appertains to make and use the same.

This invention relates to a new and useful brick machine.

The invention in its broadest scope aims 15 to provide a machine of this nature, by which the plurality of bricks or the like may be formed or constructed at one time.

A further object of the invention is the provision of a movable member having a 20 number of compartments, which receives the plastic material for forming the bricks.

A further object of the invention is to provide a front plate for coöperating with the movable member whereby the bricks 25 may be completed, which front plate, when thrown in operative position operates the movable member.

A feature of the invention is the provision of a vertical movable cross head having 30 a number of transverse plates, to further complete the bricks, the same being operated by a foot pedal.

In the drawings: there is disclosed only one form of the invention, but in practical 35 fields this form may necessitate alterations, to which the patentee is entitled, provided the alterations are comprehended within the scope of what is claimed.

The invention comprises further features 40 and combination of parts, as hereinafter set forth, shown in the drawings and claimed.

In the drawings:—Figure 1 is a view in perspective, showing the moving parts of the machine closed. Fig. 2 is a similar view 45 showing the moving parts opened. Fig. 3 is a vertical sectional view on line 2—2 of Fig. 1. Fig. 4 is a sectional view on line 4—4 of Fig. 1. Fig. 5 is a sectional view on line 5—5 of Fig. 2.

Referring more specifically to the drawings 50 1 designates the main frame, which may be of any desired construction and contour, but preferably constructed of angle sheet metal and plain bars, as shown at 2, 3, 4 and 5. This frame supports a plate 6, the rear portion of which upon its upper

surface is provided with a series of grooves 6^b, which extend for half the length of the plate, that is, from substantially the center portion of the plate rearwardly. This plate 6 is also constructed with a slot 50^b, the purpose of which will hereinafter appear. The forward portion of the plate 6 has its upper surface disposed below the bottoms of the grooves 6^b, as shown and disposed upon this 60 upper surface of the forward portion of the plate 6 is the bed plate 6^a, the upper surface of which is flush or even with the bottoms of said grooves 6^b, the purpose of which will appear later. Above the plate 6 a supplemental frame 7 is supported by the bars 8, that is, above the rear portion of the plate 6. This supplemental frame 7 supports a hopper 9 of galvanized sheet iron, through which the plastic material is passed into the 70 plurality of compartments 10 of the movable member 11. This movable member 11 reciprocates upon the upper rear surface of the plate 6, the divisional plates 12 (which form the compartments 10) of the member 80 11 slide in the grooves 6^b. However, when the movable member is moved forwardly, the divisional plates 12 slide from the grooves 6^b forwardly and upon the bed plate 6^a as shown in Fig. 2. The movable 85 member, however, is moved forwardly after the compartments 10 have been filled with the plastic material.

Carried by the sides of the main frame, two on each side, are the brackets 13, in 90 which the side tubular bars 14 of the U-shaped frame 15 are seated. These side tubular bars are secured in the brackets by the bolts 16. Slidable on the side tubular bars 95 is the cross head 18, there being two bars 19 and 20, which constitute the cross head; while the annular members 21 (which are bolted at 22 to the bars 19 and 20) constitute the sliding bearing. Secured to the cross bars 19 and 20 are the vertical plates 23, at the lower ends of which the transverse plates 24 are rigidly secured. The plates 24 shape and smooth one side of the bricks, when brought in operative position as shown in Fig. 1, while the compartments 10, form 100 two sides and an end of the brick. The base plate forms the side of the brick opposite the sides formed by the plates 24. The vertical plates 23 are further secured to the cross bars 19 and 20 by the crossing 110 bars 25. Connecting the end vertical plates 23 is a U-shaped handle 26, which

may be used for lowering the cross head if desired. However this cross head is preferably lowered by the treadle 27 which is pivoted at 28, and connected to two of the annular members or bearings 21 by the rods 28^a. These rods are connected to the annular or bearing members by means of the bolts 29. Coiled springs 30 are connected between the cross bar 31 of the treadle 18 and the under portion of the bed plate, which springs normally hold the treadle and the cross head in their raised position. The cross bar 31 is connected to the treadle by the U-shaped members 32.

15 Mounted in bearings 33 of the main frame is the shaft 34. Pivoted on the shaft is the front plate 35, which is provided with the plates 36. The plates 36 are equally spaced apart, as shown at 37, so as to receive the forward edges of the division plates 12 of the movable member 11, that is, when the front plate 35 is closed as in Fig. 1. This front plate 35 is provided with handles 38, by which the same may be swung on the pivot rod or shaft 34. These handles beyond their connection 39 with the rod 34 are provided with approximately right angle extending arms 40, between which and the movable member 11 the links 41 are connected.

30 The pivot connections 40^e and 40^f between the links 41 and the arms 40 of the levers 38, and the member 11, are arranged in a plane above the rod 34, as shown in Fig. 3, by the dotted line 40^e, so as to hold the front plate 35 and the member 11 closed. The front plate necessarily has to be partially moved, in order to permit the weight 51 to open the parts of the machine by its gravitation. It will be observed that, as the front plate 35 is swung downwardly as shown in Fig. 2, the movable member 11 will be simultaneously moved rearwardly. The front plate 35 when closed is locked in position by the U-shaped lever 43, which is pivoted at 44 between the arms 44^b and the supplemental frame 7. The rear ends of the bars of the U-shaped lever 43 have slot and bolt connections 45 with the arms 46, which project upwardly from the plate 6 upon each side of the machine. The slots of the slot and bolt connections 45 between the arms 46 and the U-shaped lever 43 limit the upward movement of the forward end of the U-shaped lever 43.

55 When the front plate 35 is closed as shown in Fig. 1, the notches 46^a of the U-shaped lever 43 engage the recesses 47 of the two end plates 36, so as to hold the front plate locked, until the bricks have hardened sufficiently. By virtue of the slot and bolt connection 45, the U-shaped lever 43 may be tilted upon its pivot 44, so that the front plate may be opened. The U-shaped lever 43 is provided with a handle 48, by which the lever may be raised.

Traveling over the pulleys 49 is a cable 50, substantially the central portion of which is secured at 50^e to an arm 50^f (which moves backwardly and forwardly in the slot 50^b when the member 11 is reciprocated) secured at 50^g by any suitable means to the member 11. One end of the cable is provided with a weight 51, while the other end is connected to the cross bar 31 of the treadle 27 by means of the hook 52. After the U-shaped lever 43 is raised, thus releasing the front plate 35, the movable member 11 may be moved rearwardly and the front plate thrown downwardly by the gravitation of the weight, that is, when the handles or 80 levers 38 are partially moved outwardly and downwardly upon the pivot rod 34 manually until the pivot 40^e is below the plane between the pivot rod 34 and the connection 40^f. Then the weight will act to move the member 11 rearwardly and the front plate downwardly, the operator's foot having first been removed from the treadle. When the operator's foot is removed from the treadle, the cross head with the plates 23 and 24 will be thrown to their uppermost positions, thereby leaving the bricks upon the bed plate 6^a ready to be removed.

Operation: In operating the machine the parts thereof assume positions as shown in Fig. 2, that is, without any bricks upon the bed plate 6^a. When the parts are so arranged the movable member 11 with the divisional plates 12 forming the compartment 10 are under the hopper 9, the divisional plate being received in the slots 6^b. The plastic material is then placed in the hopper passing therethrough into the compartments 10. The operator then throws the handles or levers 38 upwardly, and owing to the arms 40 being connected to the links 41 at 40^e, which links in turn pivotally connect at 40^f to the member 11, the member 11 will be moved forwardly, the divisional plates 12 passing from the grooves 6^b upon the bed plate 6^a, the compartments 10 carrying the plastic material forwardly. When the handles or levers 38 are moved upwardly to the positions in Fig. 3, the front plate 35 is closed, and owing to the pivots 40^e being on a plane above the rod 34, as shown by the dotted line 48, the front plate 35 and the member 11 will be held closed or locked. The weight tending to pull the member 11 rearwardly, will render the locked or closed positions of the member 11 and the front plate 35 more secure. The operator then presses upon the treadle against the action of the springs, thereby lowering the cross head and the plates 23 and 24. In this manner the bricks are formed. After the front plate 35 is closed, the U-shaped lever 43 is moved downwardly, so that the notches 46^a of the U-shaped lever will engage the recesses 47 of the two end plates 36, thereby 130

holding the front plate more securely locked, until the bricks have hardened sufficiently. To permit the bricks to harden, while all the brick forming parts are closed, the treadle 5 may be held down by any suitable means such as a catch or the like (not shown). After the bricks have settled or hardened sufficiently, the handles or levers 38 may be moved manually partially outwardly, after 10 first having raised the U-shaped lever 43 until the pivots 40° are below the plane of the shaft or rod 34, then at this period of opening the brick forming parts of the machine the treadle may then be released, and by 15 means of the weight the member 11 and the front plate 35 will be thrown simultaneously to open position, and at the same time by means of the spring-tensioned treadle, the cross head together with the plates 23 and 20 24 will be raised. However, the treadle need not be held downwardly for any period of time, but after being depressed, so as to throw the plates 24 downwardly, so as to produce smooth surface upon the plastic material 25 of the bricks, the treadle may be released, and the plates 24 thrown upwardly, in this case the cable or rope between the cross bar of the treadle and the arm 50° will become loose, but nevertheless the member 30 11 and the front plate 35 will be held securely closed or locked, until it is thought the bricks have sufficiently hardened, after which the front plate 35 may be thrown partially outwardly, and as the pivots 40° pass below the shaft or rod 34, the weight will 35 then act to throw the front plate 35 completely downwardly and the member 11 fully rearwardly. By means of a sudden and forceful pressure upon the treadle all 40 of the movable brick forming parts may be closed simultaneously, even throwing the member 11 and the front plate 35 to their locked positions, and then by any suitable means (not shown), as above stated, the 45 treadle may be held downwardly.

From the foregoing it will be observed that there has been produced a novel, efficient and simple machine for constructing bricks, and one which has been found to be practicable.

Said series of plates 24 when thrown downwardly are clamped between the member 11 and the front plate 35. This is one way for holding the treadle depressed.

The invention having been set forth, what is claimed as new and useful is:-

1. In a brick machine, a frame having a bed plate, a base plate upon which said bed plate rests, a movable member having divisional plates adapted to be moved upon the base plate, said divisional plates forming compartments in which the bricks or the like are formed, said member adapted to form one end of each brick, a series of members 55 movable as one body and in a plane at

right angles to the movement of said members to form a side of each brick, a pivoted plate having means to form the other end of each brick, connections between the pivoted plate and the first movable member, a 70 gravitating member and a spring tensioned device having connections with the first movable member, the series of members and the pivoted plate, the joint actions of the gravitating member and the device constituting means whereby such members and the plate are thrown open simultaneously and held opened.

2. In a brick machine, a frame having a base plate, the upper rear surface of which is provided with grooves, the forward upper surface being recessed, a bed plate resting in the recess, a movable member having divisional plates adapted to move on the base plate, the divisional plates operating in said grooves, said divisional plates forming compartments in which bricks or the like are formed, said member adapted to form one end of each brick, a series of elements 80 movable as one body and in a plane at right angles to the movement of said member to form a side of each brick, a pivoted plate having means to form the other end of each brick, connections between the pivoted plate and the movable member, a 85 gravitating member having connections with the movable member, which in turn has connections with the pivoted plate, and a spring tensioned device having connections with the series of elements, the joint actions of the 90 gravitating member and the device constituting means whereby the movable member, the pivoted plate, and the series of elements are thrown open simultaneously and held opened.

3. In a brick machine, a frame having a base plate, the upper rear surface of which is provided with grooves, the forward upper surface being recessed, a bed plate resting in the recess, a movable member having divisional plates adapted to move on the base plate, the divisional plates operating in said grooves, said divisional plates forming compartments in which bricks or the like are formed, said member adapted to form one end of each brick, a series of elements 100 movable as one body and in a plane at right angles to the movement of said member to form a side of each brick, a pivoted plate having means to form the other end of each brick, connections between the pivoted plate and the movable member, a 105 gravitating member having connections with the movable member, which in turn has connections with the pivoted plate, and a spring tensioned device having connections with the series of elements, the joint actions of the 110 gravitating member and the device constituting means whereby the movable member, the pivoted plate, and the series of elements are thrown open simultaneously and held opened.

4. In a brick machine, a frame having a base plate, the upper rear surface of which is provided with grooves, the forward upper surface being recessed, a bed plate resting in the recess, a movable member having divisional plates adapted to move on the base plate, the divisional plates operating in said grooves, said divisional plates forming compartments in which bricks or the like are formed, said member adapted to form one end of each brick, a series of elements 115 movable as one body and in a plane at right angles to the movement of said member to form a side of each brick, a pivoted plate having means to form the other end of each brick, connections between the pivoted plate and the movable member, a 120 gravitating member having connections with the movable member, which in turn has connections with the pivoted plate, and a spring tensioned device having connections with the series of elements, the joint actions of the 125 gravitating member and the device constituting means whereby the movable member, the pivoted plate, and the series of elements 130

are thrown open simultaneously and held opened, said connections between the pivoted plate and the movable member being so constructed and arranged with relation to the pivot of said plate as to tend to hold the movable member and the plate closed.

4. In a brick machine, a frame having a base plate, the upper rear surface of which is provided with grooves, the forward upper 10 surface being recessed, a bed plate resting in the recess, a movable member having divisional plates adapted to move on the base plate, the divisional plates operating in said grooves, said divisional plates forming compartments in which bricks or the like are formed, said member adapted to form one 15 end of each brick, a series of elements movable as one body and in a plane at right angles to the movement of said member to form a side of each brick, a pivoted plate having means to form the other end of each brick, connections between the pivoted plate and the movable member, a gravitating member having connections with the movable member, which in turn has connections

with the pivoted plate, and spring tensioned device having connections with the series of elements, the joint actions of the gravitating member and the device constituting means whereby the movable member, the pivoted plate, and the series of elements are thrown open simultaneously and held opened, said connections between the pivoted plate and the movable member being so constructed and arranged with relation to the pivot of said plate as to tend to hold the movable member and the plate closed, and a U-shaped lever for holding the pivoted plate more securely locked, which in turn holds the movable member firmly forward, the series of elements being clamped between the movable member and the front pivoted plate for holding the series of elements closed.

In testimony whereof I have signed my name to this specification in the presence of two subscribing witnesses.

RICHARD G. RAND.
